UNITED STATES PATENT OFFICE.

HORACE G. CULTER, OF PEORIA, ILLINOIS, ASSIGNOR TO CULTER & PROCTOR STOVE COMPANY, OF PEORIA, ILLINOIS, A CORPORATION OF ILLINOIS.

DESIGN FOR A STOVE.

No. 39,422.

Specification for Design.

Patented July 14, 1908.

Application filed March 21, 1908. Serial No. 422,576. Term of patent 7 years.

To all whom it may concern:

Be it known that I, HORACE G. CULTER, citizen of the United States, residing at Peoria, in the county of Peoria and State of Illinois, have invented a new, original, and ornamental Design for Stoves.

In the drawing Figure 1 is a front elevation of the stove, and Fig. 2 is a side elevation thereof, both showing my new design.

I claim:—

The ornamental design for a stove substantially as shown.

HORACE G. CULTER.
